UNITED STATES PATENT OFFICE

2,492,318

NONSHACKLE PADLOCK

Norman N. Reichert, National Park, N. J.

Application June 3, 1948, Serial No. 30,931

6 Claims. (Cl. 70—32)

1

This invention relates to new and useful improvements in locks and the primary object of the present invention is to provide a lock mechanism including a pair of cooperative toothed holding members and embodying novel and improved means actuated by a correct key for forcing the holding members out of locked position for engaging an attaching member which is applied to a suitable structural element such as a chain, a latch or the like.

Another important object of the present invention is to provide a locking mechanism including a group of companion locking elements, a pair of slidable holding members forming supports for the locking elements, and novel and improved means rotated by a key engaging barrel for actuating the slidable holding members to move the locking elements toward each other and into locking engagement.

A further object of the present invention is to provide a locking mechanism that is extremely small and compact in structure and which is quickly and readily actuated to a locked position by a proper key.

A still further aim of the present invention is to provide a lock of the aforementioned character that is simple and practical in construction, strong and reliable in use, efficient and durable in operation, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary front elevational view of a door and jamb supporting a latch, and showing the locking mechanism constructed in accordance with the present invention applied to the latch;

Figure 2 is a longitudinal sectional view of the present locking mechanism taken substantially on the plane of section line 2—2 of Figure 1, and showing the holding members in a locked position;

Figure 3 is a sectional view of the present locking mechanism in an unlocked position taken substantially on the plane of section line 3—3 of Figure 4;

Figure 4 is a horizontal sectional view taken substantially on the plane of section line 4—4 of Figure 3;

2

Figure 5 is a perspective view of one of the holding members used in conjunction with the present invention;

Figure 6 is a sectional view of the present invention, and showing an attaching link engaged by the same; and

Figure 7 is a perspective view of the key receiving barrel used in conjunction with the present invention.

Referring now to the drawings in detail, wherein for the purpose of illustration, there is disclosed a preferred embodiment of the present invention, the numeral 10 represents a concavo-convex member or casing, the open end of which is rigidly secured to a closure plate or inner wall 12 having an opening or slot 14.

Mounted for sliding movement within the casing 10, are pairs of companion holding members 16 and 18. Each of these holding members 16 and 18 includes a pair of substantially triangular jaw plates 20 having bearing edges 22 and toothed edges 26. The teeth 28 of one pair of holding members 16 are adapted to be interdigitated with the teeth 28 of the remaining pair of holding members 18, therefore, the teeth 26 are staggered relative to teeth 28.

Rotatably positioned within the casing 10 is a ring 30 having a toothed portion 32 that includes a segment of the inner edge of the ring 30 for a purpose which will later be more fully apparent.

The numerals 34 and 36 represent a pair of carriers or bifurcated slide members that are slidably received in radial recesses 37 in the inner face of the wall 12. These members 34 and 36 are provided with longitudinal slots 39 that slidably receive the ring 30. The members 34 and 36 each include bearing surfaces 40 that abut the bearing surfaces 22 of the holding members 16 and 18, and the holding members 16 and 18 are held fixed to the furcations of the members 34 and 36 by pins 41.

Fixed to the lower portions 42 of the wedge members 34 and 36, are guide pins 43 that are slidably received in tangential guide slots or openings 44 formed in the ring 30. So that as the ring 30 is rotated, the members 34 and 36 will move radially toward or away from each other, depending of course whether the ring is rotated clockwise or counter-clockwise, to urge the holding members into or out of a locked position.

Rotatably carried by the casing 10 is a known and conventional key barrel 46 having a key receiving opening 48 that opposes a suitable opening in the casing 10. Fixed to the innermost end of the barrel 46 is an annular, toothed gear

50 that engages the toothed portion 32 of the ring 30.

Fixed to and projecting outwardly from the closure plate 12 is a plurality of circumferentially spaced lugs 52 that space the closure plate from a supporting structure and which also guard the exposed channel shaped end portion 54 of a substantially U-shaped attaching member 56 that is positioned in the casing 10 and which is locked within the casing 10 by the teeth 26 and 28 of the holding members 16 and 18.

It should be noted, that the end portions 54 of the member 56 are adapted to be received in an elongated slot 53 at one end 57 of a hinge to yieldingly embrace the transverse edges of the slot and retain the present locking mechanism relative thereto so that a hinge hasp staple 58 may extend through the slot 53 provided in the end of the hinge on which the present locking mechanism is applied to be locked thereto.

In practical use of the present invention, when the proper key is inserted into the opening 48 the gear 50 and barrel 46 may be rotated to rotate or actuate the ring 38 and thus slide the members 34 and 36 toward each other and the jaws 16 and 18 into locking engagement with a suitable element such as a link or the like 60.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A lock comprising a casing, a rotatable key receiving barrel carried by the casing, a plurality of slidable holding members mounted within the casing and including cooperative locking teeth, a pair of radially slidable carriers for the holding members, an internally toothed ring gear rotatable within the housing for moving the carriers toward each other, an annular gear carried by the barrel and engaging the teeth of said ring gear for rotating the latter, and interconnecting means between said carriers and said ring gear for movement of the carriers radially upon rotation of said ring gear.

2. The combination of claim 1 wherein said last mentioned means includes guide pins secured to said carriers, said ring gear having tangential slots slidably engaging the guide pins.

3. A lock comprising a casing including an in-

ner wall, a rotatable key receiving barrel carried by the casing, a plurality of toothed holding members mounted in the casing, an attaching member in engagement with the wall and having a portion projecting outwardly from the casing and adapted to engage a structural element, a pair of radially slidable carriers mounted in the casing and supporting the holding members, said holding members adapted to grip a hinge hasp staple during sliding movement of said carriers toward each other, an internally toothed ring gear, an annular toothed gear carried by the barrel for rotating the ring gear, and means connecting the carriers to the ring gear for actuating the former as the latter is rotated.

4. A lock comprising a casing including an inner wall, a rotatable key receiving barrel carried by the casing, a plurality of toothed holding members mounted in the casing, an attaching

20 member in engagement with the inner wall and having portions projecting outwardly from the inner wall and adapted to engage a structural element, a pair of slidable carriers supporting the holding members, said holding members being 25 movable with the carriers toward each other to grip a hinge hasp staple, an internally toothed ring gear, an annular, toothed gear carried by the barrel for rotating the ring gear, means connecting the ring gear to the carriers for imparting a radial movement to the latter as the former is rotated, and means for spacing the casing relative to a supporting structural element and for guarding the attaching member.

5. The combination of claim 4 wherein said last mentioned means includes a plurality of circumferentially spaced lugs carried by the casing.

6. A lock comprising a casing, a rotatable key receiving barrel carried by the casing, a plurality of slidable holding members mounted within the casing, a pair of slidable carriers supporting the holding members, an internally toothed ring gear rotatable within the casing, an annular gear carried by said barrel and engaging the teeth of said ring gear, and interconnecting means 45 between said ring gear and said carriers for movement of the carriers radially upon rotation of said ring gear.
